UNITED STATES PATENT OFFICE

164,937

AIR CONDITIONER

John E. Long, Chico, Calif., assignor to Portable
Air Cooler and Heating, Inc., Chico, Calif., a
corporation of California

Application October 10, 1949, Serial No. 5,413

Term of patent 14 years

(Cl. D62—4)

To all whom it may concern:

Be it known that I, John E. Long, a citizen of the United States, residing at Chico, in the county of Butte and State of California, have invented a new, original, and ornamental Design for an Air Conditioner of which the following is a specification, reference being had to the accompanying drawing, in which:

Fig. 1 is a perspective view of an air conditioner looking at the front and one side thereof, and showing my new design.

Fig. 2 is a perspective view of the air conditioner looking at the rear and the opposite side thereof.

I claim:

The ornamental design for an air conditioner, as shown.

JOHN E. LONG.
